UNITED STATES PATENT OFFICE.

WILLIAM S. GEORGE, OF EAST PALESTINE, OHIO.

DESIGN FOR A PITCHER OR SIMILAR ARTICLE.

Application filed October 19, 1922. Serial No. 4,039. Term of patent 7 years.

To all whom it may concern:

Be it known that I, WILLIAM S. GEORGE, a citizen of the United States, residing at East Palestine, in the county of Columbiana and State of Ohio, have invented a new, original, and ornamental Design for a Pitcher or Similar Article, of which the following is a specification, reference being had to the accompanying drawing, forming a part thereof.

Fig. 1 is a plan view and Fig. 2 a side elevation of a pitcher or similar article showing my new design.

I claim:

The ornamental design for a pitcher or similar article substantially as shown.

In testimony whereof I affix my signature, in the presence of two witnesses.

W. S. GEORGE.

Witnesses:

R. N. LOGAN,
W. D. FORNEY.
